(57) **CLAIM**

The ornamental design for a knee support with elastic band as shown and described.

DESCRIPTION

FIG. 1 is a perspective view of a knee support with elastic band, showing the new design in a position of use;

FIG. 2 is a front view of the knee support with elastic band of FIG. 1;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict elements of the knee support with elastic band that form no part of the claimed design.

1 Claim, 7 Drawing Sheets
